UNITED STATES PATENT OFFICE.

LAWRENCE C. FURTON, OF DETROIT, MICHIGAN.

CIGAR-HOLDING DEVICE.

Application filed February 16, 1922. Serial No. 536,874.

To all whom it may concern:

Be it known that I, LAWRENCE C. FURTON, a citizen of the United States of America, residing at Detroit, in the county of Wayne, and State of Michigan, have invented certain new and useful Improvements in Cigar-Holding Devices, of which the following is a specification, reference being had therein to the accompanying drawings.

The users of cigar and cigarette holders are often troubled by cigars and cigarettes becoming detached from the holders after having been placed therein, and this is particularly true in connection with cigar holders because cigars are of different shapes and one cigar may not fit as well in a holder as another cigar. To prevent a cigar or the like from becoming displaced I furnish a holder with means by which a cigar may be clamped and held in a holder, said means being in the form of an attachment that may be applied to an ordinary cigar holder, and in some instances the cigar clamping means may form a permanent part of any metallic trimming mounted on the holder.

My invention further aims to provide cigar clamping means that may be easily actuated when placing a cigar in engagement with a holder and the clamping means is such as not to injure the cigar or interfere with smoking the same in the usual manner.

In carrying my invention into effect, I have devised two forms of a holder, said forms differing particularly in the pivotal arrangement of the cigar holding members and the construction of each form will be hereinafter specifically described and then claimed.

Reference will now be had to the drawing, wherein

Figure 1 is a perspective view of one form of the cigar clamping device;

Fig. 2 is a plan of the other form of device;

Fig. 3 is a side elevation of the same, and

Fig. 4 is a developed view of the holder member shown in Figs. 2 and 3.

Reference will first be had to Fig. 1 showing a conventional form of cigar holder 1 having a mouth piece 2 at its inner end and a collar 3 at its outer end. Clamped about the holder 1, adjacent the collar 3, is a metallic band 4 preferably made of metal, the

band in its embryo form being in the form of a strip which has one end thereof reduced or shaped to provide a malleable tongue 5, and the opposite end of the strip is provided with an opening 6 through which the tongue 5 may extend and be bent to hookform to hold the ends of the strip together, thus completing a band that is frictionally held or clamped on the holder, and the collar 3 of said holder will prevent longitudinal movement of the band in one direction should it become loose.

The strip from which the band 4 is formed may be cut and stamped from sheet metal and in so cutting the strip one edge thereof is provided with resilient arms 7, said arms being in opposed relation at the front edge 70 of the strip after it is clamped on the holder 1. The resilient arms 7 receive a double bend at the band 4 with the innermost bent portion 8 apertured, as at 9, and the outermost bent portion 10 lending resiliency to 75 each arm.

Extending through the apertures 9 of the innermost bent portions 8 of the resilient arms 7 are cigar clamping members 11 said members being securely mounted in the apertures 9 so as to laterally pivot in the innermost bent portions 8 of the resilient arms 7. The cigar clamping members 11 are in the form of comparatively flat strips having the outer ends thereof provided with semi-cylindrical cigar engaging heads 12 which are adapted to cooperate in embracing a cigar 13 having its inner end in the outer end of the holder 1, as is the usual practice. The outer ends or heads 12 of the cigar holding members 11 are engaged by the resilient arms 7 and said arms are sprung outwardly by the cigar holding members when the cigar 13 is clamped between the heads 12. The resilient arms are therefore stressed to the extent of producing constant pressure against the heads 12 when engaging the cigar 13 and it is this clamping action that retains the cigar within the holder 1 against accidental displacement.

After the clamping members 11 are placed in the apertures 9 of the resilient arms 7, the inner ends of the clamping members 11 are enlarged, flattened or curved to form finger pieces 14 which may be pressed towards the walls of the holder 1 to separate

or open the heads 12 so that the cigar may be removed from between the heads and out of the holder 1, particularly after the greater part of the cigar has been smoked, or 5 burned.

Reference will now be had to Figs. 2 to 4 inclusive showing another form of my invention wherein the band or holder attachment takes the form of an oblong flat malleable link 15 having a tongue 16 at one end thereof which is bent into engagement with the opposite end of the link to clamp said link about the holder 1, similar to a band.

15 The link 15, intermediate its ends, has transverse members 17 and resilient arms 18, said arms being at the inner edge of the link and on the outer edge of the link are sets of apertured lugs 19. Pivottally mounted 20 between the sets of lugs 19, by pins 20, rivets or other fastening means are cigar clamping members 21 having the outer ends thereof provided with cigar engaging heads 22, similar to the heads 12. The inner ends of the 25 clamping members 21 terminate in finger pieces 23 normally engaged by the resilient arms 18 and said finger pieces may be pressed towards the holder 1 to further separate the cigar engaging heads 22 and 30 release the cigar 13.

The cigar clamping device may be made of light and durable metal finished to present a neat and attractive appearance on the holder 1, either as an attachment thereto or 35 as a fixture on the holder, it being possible in some instances to slip the attachment from the inner end of the holder so that the same may be discarded should a cigar snugly fit within the holder 1 and not require additional holding means.

It is thought that the utility of my device will be apparent without further description, and while in the drawing there is illustrated the preferred embodiments of my 45 invention, it is to be understood that the structural elements are susceptible to such changes, in size, shape and manner of as-

sembly, as fall within the scope of the appended claims.

What I claim is:—

1. A cigar or cigarette holding device for attachment to a holder and comprising a sheet metal band formed with integral spring arms extending laterally from said band and interlocking means on the ends of the band for detachably holding the band in place upon a holder, a pair of holding arms pivotally attached to said band intermediate their ends with said spring arms engaging said holding arms, said arms being formed with head portions curved transversely to embrace a cigar in the holder, said holding arms being extended beyond the end of said holder.

2. A cigar or cigarette holding device for attachment to a holder and comprising a metallic band to embrace the holder and detachably hold the device in place upon the holder, said band being formed with an opening adjacent one end and a bendable tongue upon its opposite end to engage said opening, said band being also formed with integral laterally extending spring arms and pairs of outwardly extending lugs in longitudinal alignment with said spring arms, and holding arms pivotally supported intermediate their ends between said lugs with an end portion of each arm engaged by the adjacent spring arm to hold said arms turned upon their pivotal supports, said holding arms being formed with heads extended and curved transversely of said holding arms to embrace a cigar held in the holder, said holding arms being extended beyond the end of said holder to engage said heads with the cigar at a distance beyond the end of the holder.

In testimony whereof I affix my signature in presence of two witnesses.

LAWRENCE C. FURTON.
